(57) **CLAIM**

The ornamental design for a table frame assembly, as shown and described.

DESCRIPTION

FIG. 1 is a perspective view of a rod component for a table frame assembly showing my new design, separately for clarity of disclosure;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a stand component for the table frame assembly showing my new design, separately for clarity of disclosure;

FIG. 9 is a front view thereof;

FIG. 10 is a rear view thereof;

FIG. 11 is a left side view thereof;

FIG. 12 is a right side view thereof;

FIG. 13 is a top view thereof;

FIG. 14 is a bottom view thereof;

FIG. 15 is an exploded view showing a pair of stand components and a pair of rod components; and,

FIG. 16 is a perspective view of the table frame assembly. The dashed broken lines on each of the components in FIGS. 1-16 illustrate portions of the article that form no part of the claimed design. The dot-dash broken lines represent the boundaries of the claim and form no part thereof.
